(57) **CLAIM**

The ornamental design for a corner fitting storage receptacle, showing my new design.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front elevational view of a corner fitting storage receptacle showing my new design;

FIG. 2 is a side elevational view thereof;

FIG. 3 is an adjacent side elevational view thereof;

FIG. 4 is a top plan view thereof;

FIG. 5 is a second embodiment of a top plan view thereof;

FIG. 6 is a top, and front perspective view thereof; and,

FIG. 7 is a top and rear perspective view thereof.

The broken line disclosure in the views is understand to form no part of the claimed design.
